CLOCK

Leo I. Bruce, Framingham Center, Mass., assignor to General Electric Company, a corporation of New York

Application May 13, 1954, Serial No. 30,478

Term of patent 3½ years

(Cl. D42—7)

In the drawing the single figure is a front perspective view of a clock illustrating my new design.

The opposite side of the clock is the same in appearance as the side shown. The plain back is provided with the usual adjusting knobs.

I claim:

The ornamental design for a clock, as shown and described.
